US0D1082880S

(12) **United States Design Patent** (10) **Patent No.:** **US D1,082,880 S**
(45) **Date of Patent:** **** Jul. 8, 2025**

(54) **WEARABLE ROBOT**

- (71) Applicant: **Samsung Electronics Co., Ltd.**, Suwon-si (KR)
- (72) Inventors: **Jong-Deuk Son**, Suwon-si (KR); **Ji-yun Park**, Suwon-si (KR); **Jeonghan Song**, Suwon-si (KR)
- (73) Assignee: **SAMSUNG ELECTRONICS CO., LTD.**, Suwon-si (KR)

(**) Term: **15 Years**

(21) Appl. No.: **29/978,652**

(22) Filed: **Dec. 13, 2024**

Related U.S. Application Data

- (63) Continuation of application No. 29/889,797, filed on Apr. 17, 2023, now Pat. No. Des. 1,058,628.

(57) **CLAIM**

The ornamental design for a wearable robot, as shown and described.

DESCRIPTION

FIG. 1 is a front perspective view of a wearable robot showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a rear perspective view thereof;

FIG. 9 is an enlarged view of the portion 9 delineated in FIG. 1; and,

FIG. 10 is an enlarged view of the portion 10 delineated in FIG. 8.

The dashed broken lines in the figures illustrate portions of the wearable robot that form no part of the claimed design. The dot-dash broken lines in the figures delineating portions of the claimed design that are illustrated in enlargements form no part of the claimed design.

1 Claim, 10 Drawing Sheets
